UNITED STATES PATENT OFFICE

CHARLES T. WITTSTEIN, OF NEWARK, NEW JERSEY

ORNAMENTAL DISPLAY DEVICE

Application filed July 13, 1929. Serial No. 377,953.

This invention relates in general to the association of lighting effects with sound producing mechanism, for example a radio loud speaker. The pleasing aesthetic and psychological effects produced by correlation of color and music are already recognized, and one object of my invention is to provide a novel and improved apparatus for combining or correlating sound and color in a simple, inexpensive and effective manner.

Another object is to provide such apparatus including a novel and improved construction and combination of a light reflecting or light transmitting screen and means for projecting thereon colored lights, whereby infinitely varying lighting effects can be obtained.

Other objects are to provide apparatus of the character described whereby the lighting or color effects can be changed at the will of the operator instantly and with ease and without in any manner disturbing the sound reproduction; to provide such apparatus embodying a hollow spherical segment which has its interior surface polished, in combination with means for projecting light upon said polished surface; and to obtain other advantages and results as will be brought out by the following description.

Referring to the accompanying drawings in which corresponding parts are designated by the same reference characters throughout the several views,

Figure 1 is a transverse vertical sectional view taken on the line 1-1 of Figure 2 through an illuminated sound reproducing apparatus embodying my invention.

Figure 2 is a front elevation of the apparatus with portions broken away on the line 2-2 of Figure 1.

Figure 3 is a top plan view of the apparatus with portions broken away on the line 3-3 of Figure 1.

Figure 4 is a horizontal sectional view on the line 4-4 of Figure 1.

Figure 5 is a detached plan view of the disc color screen.

Figure 6 is a view similar to Figure 1 showing a modified form of the invention.

Figure 7 is a view similar to Figure 2 showing the form illustrated in Figure 6.

Figure 8 is an enlarged transverse vertical sectional view through the color screen on the line 8-8 of Figure 7.

Figure 9 is an end elevation of the color screen shown in Figures 6 and 7.

Figure 10 is a detached perspective view of the color screen.

Figure 11 is a transverse vertical sectional view through another form of the invention, and

Figure 12 is a front elevation thereof.

Specifically describing the embodiment of the invention illustrated in Figures 1 to 5 inclusive, the reference character A designates a casing having a flat top wall 1 in which is formed an opening 2 which constitutes the outlet for a sound producing mechanism which is shown as comprising a magnetic radio loud speaker unit 3 connected by a sound conducting tube 4 to the outlet opening 2.

A sounding board 5 in the form of substantially a quarter segment of a hollow sphere is mounted upon the top wall 1 above the opening 2 so as to project the sound from said opening upwardly and outwardly away from said opening. The sounding board 5 in effect forms a horn-like recess with the top wall 1 of the casing, and is substantially an extension of the sound discharging tube 4 of the sound-producing mechanism. Preferably the concave inner surface 6 of the sounding board is highly polished, although this is not absolutely essential to the invention.

A source of light, such as an incandescent electric lamp 7, is arranged within the sound discharging tube 4 below the top wall 1 of the casing and substantially in the outlet opening 2. A color screen which is in the form of a flat disc 8 is journaled upon the underside of the top wall 1 on a suitable shaft 9 with a portion extending into the opening 2 between the light source 7 and the inner side 6 of the sounding board 5. This disc may be of any suitable construction, but preferably comprises a plurality of segments 10 of different shapes and sizes and of dif-

ferent colors, and preferably the segments are formed of transparent or other light passing material, such as glass. A knob 11 is connected to the shaft 9 at the upper side 5 of the top wall 1 for rotating the disc.

In operation of the apparatus, the loud speaker unit 3 is connected to a radio receiving set in the usual manner and sound waves are discharged through the tube 4 and

10 outlet opening 2 into the stage-like recess produced by the sounding board 5 on the top wall 1. The sounding-board then projects the sound upwardly and forwardly. The lamp 7 is connected to any suitable source of 15 electricity and is lighted during operation of the apparatus, when desired, and controlled by a suitable switch (not shown).

The rays of light pass through the transparencies of the disc 8 and become colored 20 according to the colors of the segments 10, and the colored light is projected upon the polished inner surface 6 of the sounding-board. Remarkable and highly aesthetic lighting effects resembling floating clouds 25 are thus produced; and by rotating the disc 8 the color effects may be changed, that is, when the disc is rotated, different colored segments are arranged in the paths of the light rays from the lamp 7. Obviously the color

30 projected upon the inner surface 6 of the sounding-board may be changed at will to suit the operator and the particular music or the like being reproduced by the sound producing mechanism. With the inner sur-

35 face 6 highly polished, slight changes in position of the observer or the disc 8 will cause remarkable changes in color effects, and it has been found that with only two or three of the transparencies 10 of different color arranged over the lamp 7 an infinite number 40 of color tones on the inner surface of the sounding board will be produced. The conformation of the color spots or bands can of course be changed by varying the shapes of

45 the segments 10 and in other ways which will readily occur to those skilled in the art. It will be observed that the light source is concealed outside the boundaries of the concave surface 6, and that the light rays are 50 projected upon said surface from one edge thereof and in a direction approximately corresponding to the curved plane of the surface; this results in a glareless and soft blending of the colored light.

55 The sounding-board 5 in connection with the top wall 1 of the casing closely simulates a miniature stage or proscenium, so that the observer is given the suggestion of a stage performance which is especially realistic 60 where operatic or dramatic productions are being reproduced by the sound-producing mechanism. I also contemplate decorating the inner surface 6, and I may provide a plurality of removable decorations which 65 can be interchanged as desired. For ex-

ample, I may provide a channel guide-way 12 at the bottom of the sounding board 5 adjacent the top wall 1 and utilize a plurality of differently decorated flexible strips 13 which can be slipped endwise into the guide 70 12 and held thereby in close conformity with the inner surface 6. The decorations may of course be of any type, for example figures, or outdoor scenery, or a combination thereof.

In Figures 6 to 10, inclusive, I show a modified form of my invention which is in general the same as that hereinbefore described; the essential difference is the light producing mechanism. In this form of the invention, the color screen 14 is substantially cylindrical 80 and composed of a plurality of strips 15 of transparent or light passing material such as glass which are of different colors. These strips are clamped between end pieces 16 which have trunnions 17 for rotatably 85 mounting the screen in brackets 18 depending from the underside of the top wall 1 of the casing. One of these trunnions may be in the form of a tube 19 at the inner end of which is mounted an electric lamp 20, the 90 wires 21 for supplying electricity to the lamp passing through the tube 19. For rotating the screen from the exterior of the casing I may provide a polygonal socket 22 in one of the trunnions with which is adapted to 95 cooperate the polygonal end 23 of a rod 24 which passes through one end of the wall of the casing.

As shown, a segmental portion of the cylindrical screen passes through an opening 25 in the sound-discharging tube 4 beneath the outlet opening 2, and with the lamp 20 inside the screen, obviously the rays of light pass upwardly through the transparencies 15 and the opening 2 against the inner surface 6 of the sounding-board 5. The color effects thus produced may be instantly changed, at the will of the operator, by rotation of the cylindrical screen.

In Figures 11 and 12 is shown another form of the invention which contemplates the combination of a dynamic type of radio loud speaker and a radio receiving set in the same casing with the sounding board and light producing mechanism. As shown, the casing 26 has a top wall 27 like the wall 1 which is provided with an opening 28. Beneath the opening is arranged a known type of dynamic loud speaker 29 with the diaphragm 30 in substantially horizontal position and in substantially axial alignment with the opening 28. A horn-like tube 31 serves to conduct sound from the loud speaker unit through the opening 28. Radio receiving apparatus 32 may be arranged at the front of the casing, with the control dials and knobs 320 projecting from the top wall 27.

Above the opening 28 is arranged a hollow casing extension 33 in which is mounted a sounding board 34 substantially identical in 130

construction with the sounding board 5. This sounding board is pivotally mounted at 36 to the ends of the extension 33 so as to swing into the extension in surrounding relation 5 to the opening 38 as shown by solid lines in Figure 11, or to swing out of the extension 33 to close the casing and the extension 33, and enclose the dials and knobs 320, as shown by dotted lines. This type of casing is 10 shown in my Patent No. 1,585,454, dated May 18, 1926.

Within the opening 28 and journaled upon a suitable bracket 37 is a color screen disc 38 which may be identical with the disc 8 hereinbefore described. The disc is rotatable by a 15 knob 39. Beneath the disc is arranged an electric lamp or other light source 40 with which cooperates a reflector 41 for directing rays of light upwardly through the disc 38 20 against the inner surface of the sounding-board 34.

The operation of this form of the invention is substantially the same as that hereinbefore described, the radio receiving apparatus 32 actuating the loud speaker 29 to reproduce sound which is projected through the opening 28 and sounding-board 34 which is illuminated.

While I have shown and described a certain 30 relation between the loud speaker 29, the lamp 40, disc 38 and sounding-board 34, I do not desire to be limited to this specific arrangement which is intended primarily as illustrative of the principles of my invention.

35 Interchangeable decoration sheets 42 may be utilized in connection with the sounding-board 34 just as described in the construction shown in Figure 1.

While I have shown the invention embodied in certain details of construction, it should be understood that it is within the scope of the invention to utilize the invention in connection with other sound-producing or sound reproducing apparatus, and that the 45 details of construction may be modified and changed by those skilled in the art without departing from the spirit or scope of the invention.

Having thus described my invention, what 50 I claim is:

1. An ornamental display device, comprising an opaque member having an exposed segmental spherically concave surface, and means concealed outside the boundaries of 55 said surface of said member adjacent one edge thereof to project light rays of different colors simultaneously upon said surface, from said edge thereof, whereby said colors are blended on the surface to produce an ornamental effect by reflection of the light rays from one portion of said surface to other portions thereof.

2. An ornamental display device, comprising an opaque member having an exposed 60 segmental spherically concave surface, a

source of light concealed outside the boundaries of said surface adjacent one edge thereof, and a rotatable member having different colored transparencies arranged between said light source and said concave surface, whereby light rays of different colors may be selectively projected upon said surface of said member from said edge thereof and the different colored light rays are blended on said surface by reflection of the light rays from 70 one portion of said surface to other portions thereof.

CHARLES T. WITTSTEIN.
